UNITED STATES PATENT OFFICE.

HENRY JUDSON BURROUGHS, OF LOS ANGELES, CALIFORNIA.

ORE-SEPARATOR.

SPECIFICATION forming part of Letters Patent No. 752,027, dated February 16, 1904.

Application filed January 28, 1903. Serial No. 140,861. (No model.)

To all whom it may concern:

Be it known that I, HENRY JUDSON BURROUGHS, a citizen of the United States, and a resident of Los Angeles, in the county of Los Angeles and State of California, have invented new and useful Improvements in Ore-Separators, of which the following is a full, clear, and exact description.

My invention relates to certain novel and useful improvements in mechanism for separating precious metals from their ores.

In carrying out the present invention I have particularly in view the production of a separator of the character specified which may be easily and readily assembled in position for use and which shall be simple in construction and capable of standing the strain and wear and tear to which it is subjected while in operation.

A further object of the invention is to provide mechanisms or devices for adjusting or raising and lowering the cylindrical water-tank of the separator relative to the mercury or quicksilver tank, the adjusting means being such that they will occupy but little space, will not be easily injured, and are very positive and satisfactory in operation.

With these and other objects of a similar nature in view my invention consists in the peculiar construction, combination, and arrangement of parts, as will be hereinafter described in this specification, delineated in the accompanying drawings, and set forth in the appended claims.

Although I have hereinafter shown and described one specific embodiment of my invention, I do not wish to be considered as limiting myself to the precise details thereof, as there may be modifications and variations in some respects without departing from the spirit of the invention or sacrificing any of the advantages thereof.

Reference is to be had to the accompanying drawings, forming a part of this specification, in which similar characters of reference indicate corresponding parts in all the figures.

Figure 1 is a top plan view of an ore-separator embodying my invention. Fig. 2 is a side elevation of the same, and Fig. 3 is a cen-

tral vertical sectional view of the feed-pipe and funnel therefor.

In the accompanying drawings, wherein an embodiment of my invention is illustrated, the letter A designates the frame of the separator, which is constructed of any suitable material, such as wood or metal, and, as shown, in the present instance it is formed of top and bottom frames 1 and 2, respectively, substantially quadrantal in shape, such frames being spaced apart and connected by vertical standards 3. A beam or brace of similar material, as at 4, connects the vertical standards centrally thereof, and a similar beam, as at 5, extends transversely of the top frame 1. Resting on the bottom portion of the aforesaid main frame, as shown at 6, is a relatively shallow pan approximately circular in contour, adapted when the separator is to be used to contain mercury or quicksilver, and for the sake of convenience I shall hereinafter designate this receptacle the "mercury-pan." Suspended above the mercury-pan is a cylindrical casing 7, open at both ends, the said casing or cylinder being of substantially the same dimensions transversely as the aforesaid mercury-pan, the lower edge of said cylinder 7 being adapted to be brought into contact with the upper edge of the mercury-pan 6 and held in such abutting position, so as to form a tight joint therewith, the mercury-pan and the cylinder in such instance being to all intents and purposes one vessel. This open cylinder is supported in the framework in such manner that it may be adjusted vertically relative to the aforesaid mercury-pan, and means employed for accomplishing such an adjustment are clearly shown in Figs. 1 and 2. Secured to each corner of the top portion of the aforesaid main frame are plates, as shown at 8, extending inwardly and carrying at their ends 90 collars or sleeves, as at 9, which collars or sleeves are preferably interiorly screw-threaded and form bearings for the screw-rods 10. Such screw-rods are in turn at their lower ends connected with the aforesaid cylinder 7 by means of the brackets 11, which are provided at their outer ends with sleeves or collars 12. As will be observed by reference to

Figs. 1 and 2, there are four of these screw-rods and four corresponding brackets, the said brackets extending radially from the cylinder. Mounted approximately near the top of each of the aforesaid screw-rods 10 is a horizontally-disposed sprocket-wheel 13, the teeth of which are adapted to engage the endless chain 14, which extends around the aforesaid sprocket-wheels. It will further be seen that one of the aforesaid screw-rods 10 is provided with a hand turning-wheel 15, by means of which the aforesaid screw-rod carrying said wheel is turned or revolved in its bearing. By turning the wheel the chain is caused to travel around said sprocket-wheel and in doing so will cause the revolution of each of the aforesaid screw-rods 10 in the collars or brackets of the cylinder, which will consequently cause the aforesaid cylinder to be raised or lowered vertically relative to the mercury-pan.

Extending upwardly from the transverse standards or beams of the top frame 1, approximately centrally thereof, are the brace-rods 16, which support at their upper terminals a collar, as at 17. This collar 17 in turn forms a bearing for the funnel portion 18 of the feed-pipe, said funnel portion being connected with the vertically-arranged tubular feed-shaft 19 through the medium of a short section of piping 20. The lower end of the aforesaid tubular section 19 carries a hub, as at 21, to which hub are fastened the radially-extending inclined beater-blades 22, which, as will be seen, extend circumferentially around the aforesaid hub and are inclined relatively to the axis thereof. When the machine is in operation, these blades are in a position a little above the mercury-pan for a purpose to be herein-after described, and to cause a revolution of the fan or blades I have secured rigidly to the upper end of the aforesaid tubular shaft 19 a horizontally-disposed bevel-gear 23, which is adapted to be driven by a similar vertically-disposed bevel-gear 24 meshing therewith. It will be seen by reference to Fig. 2 that the gear 24 is revolved through the medium of a shaft 25 and supported horizontally on the top of the frame 1 in bearings or clamps 26, such shaft being turned or driven from a belt-pulley 27 by power obtained from any suitable source.

From the above description of the construction of the machine and the arrangement of the parts the operation may be readily understood. The precious-metal-bearing material is fed into the machine through the funnel 18 and drops down through the tubular shaft 19. The cylindrical shell or casing 7 having in the meantime been screwed or adjusted so that it abuts or contacts with the mercury-pan, as above described, and the pan 6 having therein mercury or quicksilver, water is poured in or supplied to the cylinder 7. When the metal-

bearing material has been emptied into the cylinder through the funnel 18 and the shaft 19, the aforesaid shaft 19 and the fan or blades carried thereby are revolved through the medium of the gearing above described, and such material is then by centrifugal force forced outwardly against the walls of the cylinder. Owing to its specific gravity, the gold will of course drop or fall downwardly through the mercury to the bottom of the pan, and the dirt or foreign matter which has been separated from the gold will rest upon the mercury in the pan. When it is desired to remove such foreign matter from the pan, it is only necessary to elevate the cylinder through the medium of the mechanism before described, and the water will immediately rush out through the opening or space thus formed between the mercury-pan and the cylinder and carry with it such foreign matter. The mercury-pan may then be removed and the gold collected in the usual manner.

Having thus described my invention, I claim as new and desire to secure by Letters Patent—

1. A separator comprising a main frame, a two-part separating-tank therefor, means for adjusting one portion of said separating-tank vertically relative to the other, a feeder for said tank, and means for revolving the feeder, substantially as set forth. 95

2. A separator comprising a main frame, a tank formed of two portions, an upper open portion and a lower pan-like portion, means for adjusting the upper portion vertically relative to the other pan portion, such means comprising bearing-brackets secured to said upper portion, bearings mounted on the main frame, screw-rods extending through the said bearings on the main frame and engaging with the brackets on the upper portion of the tank, sprocket-gears carried by said screw-rods, and an endless chain extending around said gears, the construction being such that when the chain is in motion, the gears and the screw-rods will be revolved and the upper portion of the tank adjusted vertically, substantially as set forth. 100 105

3. A sectional separator comprising a main frame, a separating-tank, means for moving one section of the tank relative to another, and means for feeding and distributing precious-metal-bearing material in said tank, such means comprising braces on the main frame, carrying a collar, a funnel supported by said collar, a tubular shaft revolvably supported in the main frame and communicating with said funnel, a fan carried by the part of the tubular shaft in said tank, and means for revolving said tubular shaft, substantially as set forth. 115 120 125

4. A separator comprising a two-part tank, means for adjusting one of said parts vertically relative to the other, a revolvable feeder

- carrying a fan extending into said tank, and means for revolving said feeder, substantially as set forth.
5. A separator comprising a two-part tank, means for adjusting one of said parts vertically relative to the other, a revoluble feeder carrying a fan extending into said tank, means for revolving said feeder, said means comprising a bevel-gear carried by said feeder, 10 a second gear intermeshing with the bevel-gear of the feeder, and means for revolving the second gear, substantially as set forth.
6. In a separator, a tank formed of sections, and screw-rods connected with one section of the tank for adjusting said section relative to another section of the tank, substantially as set forth.
- 15 7. In a separator, a main frame, a separating-tank formed of two sections, and means mounted on the main frame and connected with one of the sections of the tank for adjusting said tank-sections vertically relative to the unconnected tank-section, substantially as set forth.
- 20 8. In a separator, a tank formed of two sections, and mechanism including a plurality of sprocket gear-wheels, and an endless drive-chain extending around said sprocket-wheels, for adjusting one section of the tank relative 25 to the other, substantially as set forth.
9. A separator comprising a main frame, a separating-tank formed of two portions, a pan-like portion and a cylindrical portion mounted above the pan-like portion, and mechanism 30 mounted on the main frame and connected with the cylindrical portion of said tank, for adjusting said cylindrical portion vertically relative to the pan-like portion, substantially as set forth.
- 35 10. A separator comprising a main frame, 40 and a two-part separating-tank, means for adjusting one part of said tank vertically relative to the other, each means comprising screw-rods mounted in bearings on the main frame, and connected with a portion of said tank, 45 horizontally-disposed sprocket-gears on the screw-rods, a chain extending around said gears, and a hand-wheel for turning one of said screw-rods in its bearing to actuate the aforesaid chain, substantially as set forth. 50
11. A separator comprising a main frame, a tank therefor, a feeding device for supplying ore to the tank, such feeder comprising a revoluble, tubular shaft, beater-blades mounted on said shaft at an inclination to the axis 55 of rotation of the shaft, and a stationary funnel connected with the shaft, substantially as set forth.
12. A separator comprising a tank adapted to contain mercury, a cylindrical section 60 adapted to be brought into abutment with said mercury-tank, means for adjusting said cylindrical section vertically, relative to the mercury-tank, a feeding device for supplying precious-bearing material to the tank, such feeding devices comprising a vertically-arranged tubular shaft carrying a fan at its lower end, a stationary funnel connected with said tubular shaft, and means for revolving the tubular shaft and its fan in the tank, substantially as 65 set forth.
- 70 In testimony whereof I have signed my name to this specification in the presence of two subscribing witnesses.
